(57) **CLAIM**

The ornamental design for a condom, as shown and described.

DESCRIPTION

FIG. 1 is a top perspective view of a condom showing our new design;

FIG. 2 is a bottom perspective view thereof;

FIG. 3 is side view thereof, all side views being identical;

FIG. 4 is a top view thereof; and,

FIG. 5 is a bottom view thereof.

The dash-dash broken line immediately adjacent to the solid line subject matter on the shaft depicts a boundary of the claimed design. The remaining broken lines depict portions of the condom that form no part of the claimed design.
